COMBINED PAPERWEIGHT AND PENHOLDER

Leon M. Levy, Chicago, and Harry J. Lemanski, Glenview, Ill., assignors to The Gillette Company, Santa Monica, Calif.

Filed June 21, 1971, Ser. No. 155,378

Term of patent 14 years

Int. Cl. D19—02

U.S. Cl. D74—5 A

FIG. 1 is an elevational view of a combined paperweight and penholder showing our new design;

FIG. 2 is a top plan view thereof looking in the direction of the arrow 2 on FIG. 1; and

FIG. 3 is a bottom plan view looking in the direction of the arrow 3 on FIG. 1.

We claim:

The ornamental design for a combined paperweight and penholder, as shown.
